TOY AMUSEMENT RIDE

Frank D. McDonald, 1441 Federal Ave.,
Los Angeles, Calif.

Filed June 18, 1963, Ser. No. 75,408

Term of patent 3½ years

(Cl. D34—15)

The single figure is a perspective view of a toy amusement ride, showing my new design. The sides opposite the sides shown are substantially the same as those shown.

I claim:

The ornamental design for a toy amusement ride, substantially as shown and described.
